ARTICLE-SUPPORT SHOULDER BRACKET

Clifford C. Richey, Scottsdale, Ariz., assignor to
Richey's, Incorporated, Des Moines, Iowa

Filed Dec. 16, 1969, Ser. No. 20,524

Term of patent 14 years

Int. Cl. D8—03

U.S. Cl. D8—154

FIG. 1 is a frontal perspective view of an article-support shoulder bracket showing my new design;

FIG. 2 is a front elevational view thereof;

FIG. 3 is a side elevational view thereof as seen from the right of FIG. 2;

FIG. 4 is a rear elevational view thereof;

FIG. 5 is a top plan view thereof; and

FIG. 6 is a bottom plan view thereof.

I claim:

The ornamental design for an article-support shoulder bracket, substantially as shown.
